(57) **CLAIM**

The ornamental design for a card and ribbon combination, as shown and described.

DESCRIPTION

FIG. 1 is a right side perspective view of the present invention of a card with ribbon combination;

FIG. 2 is a top view thereof, with the card partially open;

FIG. 3 is a front elevational view thereof;

FIG. 4 is a left side elevational view thereof, with the card partially open;

FIG. 5 is a rear elevational view thereof, showing an inside surface where the rear of the tie down tack is attached thereto;

FIG. 6 is a right side elevational view thereof, with the card partially open; and,

FIG. 7 is a top plan view thereof showing the card partially open.
